SOUND REPRODUCING MACHINE

William D. La Rue, Philadelphia, Pa., assignor,
by mesne assignments, to Radio Corporation of
America, New York, N. Y., a corporation of
Delaware

Application January 15, 1927. Serial No. 161,440

77 Claims. (Cl. 274—10)

This invention relates to magazine sound reproducing machines and, more particularly, to machines of the type adapted to reproduce sound from disk record tablets.

5 These magazine machines usually include a magazine for holding the record tablets, means for transferring records from the magazine to the turntable, and means for automatically controlling the movements of the sound reproducing instrumentalities, whereby said instrumentalities are moved into cooperative relation with a record tablet to be reproduced and, after the reproduction of said tablet, are returned to a position suitable for the initiation of the reproduction of the next record tablet delivered to the turntable. Devices of this character, however, have heretofore been so complicated in construction, or so large in size and unpleasing in appearance, or have required driving means of 10 such size or complexity, as to render them unsatisfactory from the user's standpoint.

An object of the present invention is to provide a magazine sound reproducing machine of novel, simplified and compact construction, and 15 one which is positive in its action, whereby a plurality of disk record tablets may be automatically played in succession.

Another object of the present invention is to provide a sound reproducing machine with improved means for automatically moving the sound reproducing instrumentalities to starting position after the completion of the reproduction of 20 a record.

Another object of this invention is to provide a sound reproducing machine with improved means for moving the sound reproducing instrumentalities to starting position for tablets of different diameters.

25 A further object is to provide improved manually adjustable means for controlling the movement of the sound reproducing instrumentalities to starting position for tablets of different diameters.

Another object is to provide novel means for supporting a plurality of record tablets in position for transfer into cooperative relation with sound reproducing instrumentalities.

Another object is to provide a sound reproducing machine of the magazine type with novel means for transferring, in succession, a plurality of disk record tablets from a supporting device or magazine into cooperative relation with sound reproducing instrumentalities and, after the 30 production of each record tablet, for removing

the latter from cooperative relation with said sound reproducing instrumentalities.

Further objects of this invention are to provide a sound reproducing machine of the magazine type with novel means for automatically connecting and disconnecting the record transfer means, and the means for automatically positioning the sound reproducing instrumentalities, with and from the turntable driving mechanism; to provide improved transfer mechanism for 35 transferring record tablets of different diameters to playing position and discharging the same therefrom; to provide record tablet transfer means with adjustable mechanism whereby said transfer means may be adjusted for coaction with 40 records of different diameters; and to provide a machine of the above type which is so constructed that a single power unit may be employed for driving the various elements, and this without the necessity of introducing resistances 45 into the power circuit. Other objects will appear more fully hereinafter.

The invention is capable of receiving a variety of mechanical expressions, only one of which has been shown on the accompanying drawings, but it 50 is to be expressly understood that the drawings are for purposes of illustration only and are not to be construed as a definition of the limits of the invention, reference being had to the appended claims for that purpose.

In the drawings, wherein like reference characters refer to like parts throughout the several views,—

Figs. 21 to 24 inclusive, are enlarged perspective views of details of the mechanism illustrated in Fig. 19.

The present invention embodies sound reproducing means that are preferably mounted in a cabinet of any suitable type. In the illustrated embodiment the sound reproducing mechanism is installed in a cabinet 25, of the upright type, provided with the usual hinged cover 26, a portion only of the cabinet and cover being shown in Fig. 1. A horizontally disposed motorboard 27 is provided in the upper portion of cabinet 25, and to the underside of said board is secured, in any suitable manner, a motor 28 (Figs. 2 and 3) which, in the form shown, is an electric motor provided with power connections 29 and switch control means (not shown) of any suitable type. Preferably, motor 28 is directly attached to the lower surface of an elongated plate 30, which extends beneath a suitable opening 27a in motorboard 27, and which may be secured to the lower surface of said board at suitable points, as by means of bolts or screws, one of the latter being shown at 31 (Figs. 3 and 4).

In the preferred embodiment of the invention, the motor 28 is the only driving or power unit employed. This motor, which is in continuous operation during the actuation of the machine, is adapted to rotate the turntable and to actuate the various automatic instrumentalities. As shown, a worm drive 32 is provided between the motor shaft and a vertically disposed spindle 33 which projects upwardly through the motorboard and carries, above the latter, the usual turntable 34 which is continuously rotated. A suitable governor 35 (Fig. 3), that may be manually controlled by a thumb nut 36 and rod 37, is preferably provided for the driving motor. Mounted on the motorboard, at one side of the turntable 34, is a swinging tone arm 38 which carries, at the small end thereof, a gooseneck 39, and a sound box 40 provided with the usual stylus. The large end of the tone arm communicates with an amplifying device or horn of any suitable character. It is to be expressly understood that the invention is not limited to the type of sound reproducing instrumentalities herein illustrated.

Record tablet magazine (Figs. 1, 2, 4, and 16 to 21, inclusive)

The machine of the present invention embodies novel means for holding a plurality of disk record tablets in position to be transferred, one at a time, into cooperative relation with the turntable and sound reproducing instrumentalities. Preferably, this magazine is so constructed that the

disks are supported at their centers and in parallel planes, each disk bearing against the next adjacent disk, and somewhat inclined, from the vertical, toward the turntable.

In the form shown, this record magazine comprises a plate 42, which is pivotally mounted at its lower end, on upstanding lugs 43 which are suitably secured to and project above the upper surface of the motorboard at a point laterally spaced from the turntable 34. A cylindrical barrel 44, that is open at its inner end, extends through and is rigidly attached in any suitable manner in an aperture in the upper end of plate 42, with said open end substantially flush with the inner face of said plate. Slidably mounted within the barrel, and projecting through the open end thereof, is a tubular member 45 which carries at its outer end a circular spider or disk 46, which has a diameter less than that of the smallest record to be played, and which is rigidly held in position by means of an annular retaining member or thimble 47 that extends, for a short distance, within the cylindrical member 44. Member 47 also constitutes a centering member for the outer portion of a record supporting pin or rod that extends through and is rigidly secured to the outer closed end of barrel 44, as by means of the nut 49, the pin 48 being threaded and of reduced diameter at its outer end for engagement with the nut and to provide a shoulder for engagement with the closed end of the barrel. The projecting free end of pin 48 is provided with an upstanding ear 48a which is adapted to engage the lateral face of a record tablet 50 adjacent the center opening therein.

If desired, yielding means may be provided for maintaining spider 46 in engagement with the rear face of the innermost record tablet supported on pin 48 and to insure that as the outermost record is transferred to the turntable, the remaining records will be moved along pin 48 until the record next adjacent to the one removed will engage with ear 48a. For this purpose, pin 48 carries a coil spring 51 which has engagement at one end with the inner surface of the closed end of barrel 44 and at its opposite end with the member 47.

Means are preferably provided for locking the spider or disk 46 in retracted position in order to facilitate the positioning of a plurality of records on the pin 48 between said spider and the ear 48a. To this end the outer surface of barrel 44 may be provided adjacent its closed end with a resilient band 52 which is fixedly attached, adjacent one of its ends, to said barrel by means of a suitable screw, the free end of the band being bent to form a radially projecting thumb piece 52a. At a suitable point along the length of band 52, there is rigidly attached a pin 53 which extends radially inward from said band through an opening in barrel 44, the pin being of greater length than the thickness of said barrel. The opening in barrel 44 is of such size that the pin can slide freely therein. The portion of the pin that projects inwardly beyond the inner surface of barrel 44 is adapted to extend into a suitable opening 45a (Fig. 24) formed near the inner end of the member 45 which carries spider 46. When the spider is in retracted position, the inner end of pin 53 extends into opening 45a and locks the spider and tube 45 against movement under the influence of spring 51. By pressing on thumb piece 52a, pin 53 can be moved outwardly to free the spider. If desired, the inner end of member 45 may be provided with an inclined surface or

cam portion 45b (Figs. 20 and 24), in the radial plane of opening 45a whereby pin 53 will be forced outwardly, as the spider and member 45 are moved to retracted position, and when said last 5 named parts are in fully retracted position, pin 53 will snap into opening 45a. By this arrangement there is no necessity for forcing pin 53 outwardly clear of the tube 45, by thumb piece 52a, when it is desired to lock the spider in retracted 10 position. To insure that the opening 45a will always remain in the plane of pin 53, the member 45 may be provided with a longitudinal groove 45c which slidably receives the inner end of a pin 54 that extends through the wall of barrel 44, the 15 latter thus being held against rotation.

Means are provided for maintaining plate 42, and the records carried thereby, in a substantially upright position, said means being so constituted that plate 42 may be swung about its pivots toward a horizontal position when it is desired to close the cover 26 of the cabinet. As shown, one wall of the cabinet may be provided, on its inner face, with a suitable recess into which is fitted a flanged member 55 carrying a pivot pin 56 on 25 which is mounted a latch 57 that is adapted to extend through an opening 42a formed in the lower portion of plate 42, said opening being larger than the head of latch 57. Interposed between the wall of the cabinet and the adjacent 30 face of plate 42, and preferably on opposite sides of latch 57, are resilient members 58 (Fig. 4) which tend to move plate 42 in a clockwise direction, as viewed in Figs. 2 and 16, thereby maintaining the latter in engagement with latch 57. 35 When in normal operative position, plate 42 is slightly inclined from the vertical in the direction of the turntable 34, being yieldingly retained in this position by latch 57 and springs 58. Spider 46 may be moved by hand toward plate 42, against the tension of spring 51, until pin 53 engages the opening 45a and locks the spider in its retracted position. A plurality of records may then be slipped over ear 48a onto the pin or rod 48. By pressing down on thumb 40 piece 52a, pin 53 is withdrawn from locking position, whereupon spring 51 forces spider 46 into engagement with the face of the adjacent record, the record nearest the turntable being forced into engagement with and yieldingly held 45 against ear 48a. The records are now held in the position illustrated in Figs. 1, 2 and 19, between spider 46 and ear 48a, the edges of the records, adjacent the centering holes therein, resting on the upper surface of pin 48, in position to be 50 automatically transferred into cooperative relation with the sound reproducing instrumentalities. After all of the records have been removed from the magazine, in a manner to be more fully pointed out hereinafter, and reproduced, additional records of either 10 or 12 inch diameter, for example, may be associated with the magazine, or, if it is desired to discontinue the playing of the machine and close the cabinet, latch 57 55 may be disengaged from plate 42, and the latter may then be swung to a position above the turntable, out of the path of cover 26.

Record tablet transfer means (Figs. 1, 2, 4, and 11 to 18 inclusive)

70 The machine of the present invention embodies novel means for automatically removing record tablets in succession from the magazine, transferring the tablets to cooperative relation with the sound reproducing instrumentalities 75 and, after the reproduction of each of the rec-

ords, removing the tablet from the turntable and depositing it in a suitable receptacle.

In the form illustrated, the transfer mechanism comprises a record transfer member or hoop 59 which is pivotally mounted on lugs 60. 80 61 secured to and projecting upwardly from plate 30 intermediate the magazine and the turntable. As will be pointed out hereafter, means are provided for swinging the hoop 59 from horizontal position, surrounding the turntable, upwardly 85 to a position to engage a record supported by the magazine. The hoop 59 has an enlarged portion 59a projecting from the rear or inner side thereof, and suitable openings 62 are provided in said portion to receive horizontally disposed 90 pivot pins 63 extending through and supported by said lugs 60, 61.

Means are associated with hoop 59 whereby records of different sizes may be positively removed from the magazine and carried to the turntable. In the form shown, a block 64 (Fig. 16) is secured by screws 65 (Fig. 11) to the lower side of the enlarged portion 59a of the transfer member. Pivotally attached to the opposite ends of block 64 and projecting upwardly through 100 openings 66 and 67 in portion 59a, are two pairs of laterally spaced, record engaging members or jaws 68 and 69, the pair of jaws 68 being nearer the center of the transfer hoop than jaws 69. Preferably, the members 68 and 69 have 105 the form of bell crank levers, the lower arm of each being pivoted to block 64, and the elbows of each pair being rigidly connected by rods 70 and 71 whereby each pair of members 68 and 69 may be swung in unison, at appropriate times, 110 about their pivots, to bring the upper portions of said members flush with the upper surface of the enlarged part 59a of the transfer member. Leaf springs 72, which are secured adjacent the middle portions thereof to block 64, extend 115 beneath rods 70, 71 and yieldingly maintain jaws 68 and 69 projecting above the surface of portion 59a.

The record transfer hoop 59 is provided on its outer surface, diametrically opposite block 64, 120 with a radially projecting, slotted or bifurcated lug 59b constituting a support for a pivotally mounted record engaging member or hook 73 which projects above the upper surface of said lug and is adapted to coact with jaws 68 in removing a small sized record, for example, a 10 inch record, from the magazine and transfer it to the turntable. As shown more clearly in Fig. 13, hook 73 is pivoted at 74 to one end of an arm 75, the opposite end of said arm being pivoted at 125 76 to the lug 59b. A leaf spring 77, secured to lug 59b, extends underneath arm 75 and normally maintains the latter parallel to the plane of hoop 59 with hook 73 projected above the said lug. If pressure is exerted on the upper end of 130 hook 73, the latter is moved downwardly within the slot in lug 59b, the movement being slightly resisted by leaf spring 77.

In radial alignment with hook 73, but at a greater distance from the center of hoop 59, is a 140 hook 78, pivotally mounted on the lug 59b, that is adapted to coact with the diametrically disposed pair of jaws 69 in transferring record tablets of large diameter, for example, 12 inch tablets, to and from the turntable 34. The hooks 145 73 and 78 are yieldingly held in record engaging position by means of a suitable spring 79 secured at one end to lug 59b and at the opposite end to a pin 80 projecting from the side of hook 78. Preferably, the latter is provided with a 150

transversely extending stop pin 78a which is normally adapted to engage the outer end of lug 59b. A link 81, pivotally connected at its opposite ends to hooks 73 and 78 respectively, transmits the tension of spring 79 to hook 73 and adapts the hooks for movement in unison. In view of the manner in which hook 73 is mounted as previously pointed out, however, hook 73 may move independently of hook 78.

10 Means are provided for moving hooks 73 and 78 out of record engaging position as the hoop 59 moves to a position to deposit the record on the turntable. For this purpose, hook 78 is provided with a downwardly extending and inwardly curving arm 82 that engages the upper surface of a plate 83 (Figs. 2 and 4) as the hoop 59 moves to horizontal position. This engagement results in hooks 73 and 78 being swung about their pivots, against the tension of spring 20 79, the upper ends of said hooks moving radially out of record engaging position.

When the magazine is filled with record tablets of small size, i. e., 10 inch tablets, it will be seen that jaws 69 and hook 78 do not interfere 25 with the functioning of jaws 68 and hook 73 when hoop 59 is swung upwardly to engage said last named elements with the upper and lower edges of the outermost record on pin 48. If the magazine is filled with large sized records, i. e., 30 12 inch records, it is desirable to maintain jaws 68 flush with the upper surface of portion 59a of the transfer hoop in order that jaws 69 may properly engage the record to be moved to and from the turntable. Means are therefore provided for swinging jaws 68 about their pivots and for maintaining said jaws with their upper ends flush with the surface of portion 59a while the record hoop is in engagement with a 12 inch tablet. To this end, a shaft 84 is rotatably mounted 40 in block 64 (Fig. 16) parallel with rod 70. The outer end of shaft 84, which projects laterally from portion 59a, has rigidly attached thereto, a cam 85, and fixedly secured to the inner end of said shaft, is an upstanding arm 86 adapted to engage a pin 87 that is fixed to, and projects laterally from, a cam 88 which is slidably mounted in a slot 89 extending transversely of 45 block 64.

The upper surface of cam 88 slidably engages 50 the lower surface of enlarged portion 59a of the transfer member. The outer end of cam 88 is provided with an inclined surface 88a, the extremity of which extends over and normally rests on rod 70 that connects jaws 68. The inner end of cam 88 is reduced in thickness and slidably rests on the upper surface of rod 71. When rotary movement is imparted to shaft 84, in a manner to be described hereinafter, arm 86 acts through pin 87 to slide cam 88 longitudinally, whereupon the inclined surface 88a forces rod 70 downwardly, swinging jaws 68 about their pivots against the tension of spring 72 until the upper ends of said jaws are flush with the upper surface of the enlarged part of transfer member 55 59.

Manually adjustable means are provided for coaction with cam 85, whereby the latter is actuated during the swinging movement of the record transfer member to actuate cam 88 in the 70 manner just described. For this purpose a shaft 90 (Fig. 3) projects through the motorboard, carrying on its upper end a knurled head 90a (Fig. 1) and on the lower end thereof a bell crank lever 91. The long arm of lever 91 is provided with a downwardly extending pin 92 that

extends into a notch 93 formed in a bar 94 that is mounted for sliding movement in the direction of its length, immediately below the motorboard 27, the outer portion of said bar being provided, if desired, with a slot 95 (Fig. 11) which loosely receives supporting means, including a threaded member 96 and spacer 97, attached to the motorboard, while the inner end thereof slidably rests on the inner end portion of plate 30. Fixedly attached to the upper surface of bar 94, adjacent the inner end thereof, is a cam 98 having an inclined surface 98a and a horizontal portion 98b. Secured to the outer face of lug 61, as by means of the pivot pin 63 (Fig. 2), is a plate 99 which carries, on its inner face, a vertically disposed leaf spring 100 and, on its outer face, a cam 101 pivoted thereto as at 102. A pin 103 projects laterally from cam 101 into the plane of cam 98. Pivoted to the outer face of lug 61 is a dog 104, the upper end of which is engaged by the free end of spring 100 with the result that the lower end of the dog is forced into a notch 94a, or a second notch 94b, formed in the adjacent edge of bar 94. A rigid, L-shaped arm 105 is secured to the side of the enlarged portion 59a of the transfer member in a position to engage the upper end of dog 104 when said transfer member is in horizontal position surrounding the turntable, whereby the lower end of dog 104 is moved out of engagement with the adjacent notch in bar 94, against the tension of spring 100.

The adjustment of the transfer means for handling large sized records should be made when the hoop 59 is in horizontal position. The shaft 90 is rotated by means of knurled head 90a, thereby actuating lever 91 and pin 92 in such a manner as to slide bar 94 inwardly. Pin 103 is thus moved up the inclined surface 98a onto the flat surface 98b of cam 98, thereby swinging cam 101 upwardly, about its pivot 102, into position to be engaged by cam 85 when transfer hoop 59 is swung upwardly from horizontal position. The engagement of cams 85 and 101 results in partial rotation of shaft 84, movement of cam 88, and the lowering of jaws 68 to a position flush with the upper surface of the transfer member. Bar 94 and cam 101 are locked in position during movement of the transfer hoop by engagement of the dog 104 with notch 94b, this engagement taking place as soon as L-shaped member 105 moves out of engagement with the upper end of said dog.

Hook 73 does not interfere with the functioning of hook 78, since the engagement of the face of a large sized record with said hook 73 readily forces the same to a position flush with upper surface of lug 59b, as previously pointed out.

A suitable pointer and dial may be provided for shaft 90 on the upper surface of the motorboard to facilitate adjustment of the transfer parts for handling small or large sized records.

The action of jaws 68 and hook 73, and jaws 69 and hook 78, in removing a record from the magazine, transferring it to the turntable, and removing said record from the turntable is substantially the same. When the magazine is supplied with small sized records, the bar 64 is set with dog 104 extending into notch 94a and pin 103 resting on the upper surface of said bar, adjacent cam 98. Cam 101 is now in its lower position and will not be engaged by cam 85 to swing jaws 68. As the hoop 59 swings upwardly into engagement with the outer record, carried on pin 48, jaws 68 move into engagement with the lower

80

150

edge of said record and, due to the relation of the foremost of the records on their yieldable support 42 to said hoop 59 as it moves about the pivot members 63, and as the jaws are then moving upwardly said jaws move said record upwardly, relative to the remaining records in the magazine. The outer record is thus forced upwardly by jaws 68, sliding over the face of the next adjacent record, until the upper edge of the 10 center hole in said outer record is above the upper edge of ear 48a. As the outer record reaches this position, hook 73 engages over and yieldingly grips the upper edge of the said record to the hoop, and the record is now carried downwardly to the turntable 34 by the reverse movement of hoop 59. As the latter approaches the turntable, arm 82 engages plate 83 and hook 73 is moved out of engagement with the record as the upper end of turntable spindle 33 passes 20 through the center hole in said record. The upper end of spindle 33 is preferably tapered and by its engagement with the periphery of the center hole in the record, acts as a cam to move the record out of engagement with jaws 68, and 25 center the same on the turntable, as hoop 59 continues its movement past the upper surface of said turntable.

After the record, which has thus been transferred to the turntable, has been reproduced, it is necessary to remove the same from the turntable and to discharge it from the transfer hoop before the latter swings into engagement with the next record to be transferred to cooperative relation with the sound reproducing instruments. As the record hoop is swung upwardly, toward the magazine, jaws 68 or 69 engage the adjacent edge of the record which is carried upwardly by the engagement of the hoop 59 therewith. As the record passes out of engagement 35 with the turntable spindle, the hoop has reached a position such that arm 82 is disengaged from plate 83, whereupon hook 73, or hook 78, moves into engagement with the upper edge of the record, whereby the latter is positively swung upwardly.

Means are provided for swinging the pairs of jaws 68 and 69 to a position flush with the upper surface of the transfer member as the latter reaches a position substantially midway of the turntable and magazine, whereby the released record will slide downwardly, due to the force of gravity, across the enlarged part 59a of said transfer member into a suitable receptacle that is preferably positioned below the horizontal plane of the turntable. Referring particularly to Figs. 16 and 17, a shaft 106 is rotatably mounted in block 64 parallel to rods 70 and 71. Rigidly attached to the inner end of shaft 106 is an upstanding arm 107 which engages a pin 108 that projects laterally from a cam 109 slidably mounted in a slot 110 formed in block 64. The lower edge of cam 109 is cut away to form two inclined surfaces 109a and 109b. The outer extremity of surface 109a rests on top of rod 70 and inclined surface 109b engages the upper surface of rod 71.

The outer end of shaft 106, which projects outwardly from the enlarged part 59a of the transfer member, has fixedly secured thereto an upstanding arm 111 (Figs. 11 and 12), which has a finger 112 pivoted thereto at 113 and which carries a stop pin 114 adapted to be engaged by said finger. A suitable spring 115, secured at one end to shaft 106 and at its opposite end to finger 112, normally maintains the latter substantially at right angles to arm 111 out of engagement with pin 114. Se-

cured to lug 60, as by means of member 63, is a cam 116 which is adapted to coact with finger 112 as the latter is swung upwardly by hoop 59.

When the record transfer member arrives at the position illustrated in dotted lines in Fig. 2, finger 112 has been moved into engagement with pin 114 against the tension of spring 115, due to the movement of said finger along the surface of cam 116. Due to the contour of the surface of the latter, further movement of the hoop and finger 112 results in partial rotation of shaft 106 and consequently, longitudinal movement of cam 109. The inclined surfaces 109a and 109b of said cam swing rods 70 and 71 downwardly until the jaws 68 and 69 are flush with the upper surface of the transfer hoop. The reproduced record is now freed and slides downwardly along the hoop into the record receptacle.

If the machine is adjusted for playing large size records, the jaws 68 will be held in lowered position by engagement of cam 85 with cam 101 and the partial rotation of shaft 106 and movement of cam 109 has no effect on rod 70.

Just prior to the engagement of hoop 59 with the outer record supported in the magazine, finger 112 rides over the end of cam 116 and springs 72 swing jaws 68 and 69 outwardly to record engaging position. If the machine is adjusted for playing large size records, jaws 69 only will be returned to record engaging position since jaws 68 will be held in lowered position by cam 88 and its associated elements.

Receptacle for played records (Figs. 1, 2, 3, 4 and 19)

Means are provided for receiving the records after they have been reproduced and removed from the turntable by the record transfer means. Preferably the record receptacle is so positioned that the record tablets may move thereinto by gravity, when released from the record transfer member 59. As shown more clearly in Fig. 2, the motorboard is provided with an elongated slot 117, of a length greater than the diameter of the largest record to be played, intermediate the turntable and the magazine, and immediately below the slot 117 there is provided a receptacle 118. Preferably one wall of the cabinet forms the outer wall of the receptacle and the inner wall of the latter is constituted by a suitable partition 119 secured to the lower surface of the motorboard or to the side wall of said cabinet. In order to prevent damage to the records as they move by gravity into the receptacle, the walls of the latter are preferably covered with soft material, such as felt, indicated at 120. A hinged closure 121 may be provided for removing the records from the receptacle 118. If desired, the inner end of plate 30 may be provided with an enlarged portion 30a (Fig. 3) having a slot therein register with slot 117 to strengthen the motorboard adjacent the opening therein.

Driving mechanism for the record transfer means (Figs. 4 to 9 inclusive)

Suitable means are provided for swinging the record transfer member through a vertical arc about pivot pins 63 to a substantially vertical position whereby a record is removed from the magazine, positively carried to the turntable, and after reproduction, deposited in receptacle 118, said driving mechanism being so constituted that the record transfer mechanism is automatically thrown into and out of operation at the appropriate times. In the embodiment of the invention

tion illustrated, this driving mechanism is thrown into operation by a reverse movement of the stylus, which movement may be secured by providing a closed eccentric element, as a groove adjacent the center of the upper surface of the record. It is to be expressly understood, however, that the invention is not limited to the use of an eccentric groove for moving the stylus reversely, since other means for securing this movement will readily suggest themselves to those skilled in the art.

The driving mechanism for the record transfer means comprises a disk 122, which is loosely mounted on turntable spindle 33 and which is provided, on its lower face, with a pinion 123 that is rigidly secured to, or formed integrally with, said disk. Pinion 123 meshes with a gear 124 which is rotatably mounted on a shaft 125 rigidly secured to a plate 126 provided adjacent one end with an opening 127 which loosely surrounds spindle 33 in the plane of the pinion 123. Preferably, plate 126 is provided with a bearing portion 126a which engages spindle 33 below the plane of pinion 123.

Integral with gear 124, or rigidly fixed thereto, is a pinion 128 which meshes with a gear 129 that is rotatably associated with plate 126 by means of a stub shaft 130, which is fixed to the center of gear 129 and which carries on its upper end, a circular disk 131 that rotatably engages the upper surface of said plate. Disk 131 overlies a circular opening formed in plate 126, and secured to shaft 130, concentric with said opening and disk 131 and in the plane of said plate, is a second disk 132 of less diameter than said opening, whereby an annular slot 133 is formed, the outer edge of disk 132 constituting the inner wall of said slot. A stub shaft 134 extends upwardly through slot 133 and disk 131, and is provided on its upper end with an enlarged head 134a, which is secured in any suitable manner to said disk and which is provided, on the opposite sides of a slot 135 therein, with a pair of upstanding lugs 134b. The lower end of stub shaft 134 is rigidly attached to an elongated slide or plate 136 provided with a longitudinal slot 137 (Fig. 8) through which projects the turntable spindle 33. Plate 136 is adapted for reciprocating movement along the upper surface of plate 30. Fixedly secured to the upper surface of slide 136, adjacent the end thereof diametrically opposite gear 129, is a plate 138 provided with a cam 139 having an inclined portion 139a and a transversely extending rib 139b, for a purpose to be described herein-after.

Slidably mounted in the slot 135, provided in the enlarged head of shaft 134, is a bar 140 that is provided on its inner end with a slot 141 through which passes a pin 142 carried by a bifurcated lug 143 (Figs. 2 and 4) rigidly secured to, or integral with, the record transfer member 59. The bar 140 is provided with an elongated recess or notch 144 in its upper surface, and is retained in position in slot 135 by means of a locking plate 145, removably secured to the upper face of head 134a and provided with a tongue 145a which extends between lugs 134b carried by said head. Bar 140 may be moved in the direction of its length by engagement of head 134a with the end walls 144a and 144b of the notch 144, whereby movement may be transmitted through pin 142 to hoop 59 to swing the latter about its pivots. The notch 144 is of greater length, however, than the diameter of head 134a in order that the latter may move

through a certain distance without imparting motion to bar 140 or hoop 59.

The outer end of bar 140 is provided with a longitudinal opening 146 into which loosely extends a rod 147 provided with an enlarged head 147a, on its outer end, and with a transverse pin 148 adjacent its inner end. Pin 148 extends into a slot 149 formed in the lower surface of bar 140 and limits the movement of rod 147 relative to bar 140. Interposed between the head 147a of rod 147 and the adjacent end of bar 140, and surrounding rod 147, is a coil spring 150 which normally maintains said rod 147 in extended position where, in certain positions of bar 140, it is adapted to engage a cam 151 fixedly secured to the upper surface of plate 126.

Means are provided for connecting and disconnecting disk 122 and pinion 123 in and from driving relation with the turntable spindle 33. In the illustrated embodiment of the invention, this means is constituted by a clutch mechanism of the pawl and ratchet type and comprises a curved pawl 152 which is pivoted at 153 to the upper surface of disk 122, said pawl being provided with an inwardly projecting tooth 154 which is adapted to engage the teeth of a gear or ratchet wheel 155 (Fig. 4) that is fixedly secured, as by means of a suitable threaded member 156 (Fig. 8), to turntable spindle 33 above disk 122 and in the plane of tooth 154. A spring 157, that is secured at one end to the free end of pawl 152 and at its opposite end to a lug 158 pressed upwardly from disk 122, tends to maintain tooth 154 in engagement with gear wheel 155. Pivotal movement of pawl 152 is limited by means of a pin 159 which extends downwardly from the lower side of said pawl into a suitable opening or slot 160 formed in disk 122.

When tooth 154 is in engagement with the gear wheel 155, rotation of turntable spindle 33 sets in motion the train of gears 123, 124, 128 and 129. Since the pivot member for gear 129 is carried by plate 126 which is freely pivoted to the spindle 33, and since gear 129 has an eccentric connection through shaft 134 to the plate 126 and to the slide 136, gear 129 acts as an eccentric to oscillate plate 126 about a shaft 33 as a pivot, and to reciprocate slide 136 for a purpose to be described hereafter. Lateral movement of slide 136 is prevented by rotatable guide members 161 which are secured to the upper surface of plate 30 that is secured to the under-side of the motor-board 27.

The reciprocation of shaft 134 moves plate 145 along bar 140 until said plate 145 engages the outer end wall 144a of the notch 144, whereupon said bar 140 is moved toward the turntable spindle 33. This movement of bar 140 is transmitted, through pin 142, to the record transfer member 59, and the latter is swung upwardly about the horizontal axis constituted by pins 63 carried by lugs 60, 61.

As the record hoop moves into engagement with the outer record in the magazine, the head 147a of rod 147 engages the adjacent surface of cam 151, whereupon said rod is forced inwardly in opening 146 and spring 150 is placed under compression. Head 147a is now in a position to begin its reverse movement inwardly toward initial position. This movement, however, is not immediately effective to produce a like movement of bar 140 due to the length of notch 144, but compressed spring 150 is effective to force said bar inwardly, maintaining wall 144a of said notch in engagement with plate 145, and to thus

initiate the return movement of hoop 59. When the head of rod 147 moves out of engagement with cam 151 the weight of hoop 59 is effective to return the same to horizontal position, but the engagement of end wall 144a with plate 145 limits the rate of movement of said hoop to that of head 134a.

As the record hoop arrives in horizontal position, with its upper surface below the upper face of the turntable 34, pawl 152 is swung about its pivot 153, against the tension of spring 157, to move tooth 154 out of driving engagement with gear 155. This operation is performed by means to be described hereafter. No motion is transmitted to the gear train, plate 136, or hoop 59 during the reproduction of the record, but upon the completion thereof, pawl 152 is released, to establish the driving connection with spindle 33, and the cycle of operation just described is repeated.

Sound box and tone arm control (Figs. 1 and 3 to 10 inclusive)

Means are provided for automatically moving the sound box into operative engagement with the beginning of the record groove and, after the reproduction of the record, means are provided for elevating the sound box and swinging the same, together with the tone arm, clear of the record while the latter is removed from the turntable and a new record is placed thereon. Preferably the sound box and tone arm control mechanism is automatically thrown into operation by a particular movement of said sound box, as, for example, a reverse movement of the sound box, at the end of the record groove.

In the form shown, the tone arm 38 is provided, intermediate its ends and on the lower surface thereof, with a bracket 162 (Fig. 9) which has integrally formed therewith a tubular member 163 that extends downwardly to and through an arcuate slot 164 in the motorboard 27. Slidably mounted within tubular member 163 is a vertically disposed post 165, which extends downwardly below the lower end of said tubular member and which carries on the lower end thereof an enlarged portion 166, to which is pivoted at 167 a weighted pawl 168, the pivot being so disposed that the toe of the pawl tends to hang vertically beneath the end of the post 165. A coil spring 169 surrounds post 165 in such position that the upper end of the same engages the lower end of member 163 while the opposite end bears against the shoulder formed by the upper end of portion 166. Extending through an elongated slot 170 in member 163 and pivotally connected to the upper end of post 165, is a lever 171 which is pivoted, adjacent the central portion thereof as at 172, to a rigid arm 173 that is secured to the lower surface of the tone arm, adjacent bracket 164, or is formed integrally with the latter. The outer end of lever 171 is provided with a suitable roller 174 which has engagement with a cam 175 rigidly connected to the gooseneck 39. When it is desired to change the stylus, the sound box and gooseneck may be swung, about the usual horizontal pivot of the latter, through an angle of approximately 180° into engagement with a supporting arm 176 projecting laterally from the tone arm. Thereafter the sound box is returned to normal position to engage cam 175 with roller 174.

Means are provided for raising post 165 to disengage the stylus from the record, and for swinging said post horizontally, whereby the sound box

and tone arm are moved to one side of the turntable. In the illustrated embodiment of the invention, said means, which preferably include mechanism for controlling the engagement and disengagement of the clutch mechanism constituted by pawl 152 and gear 155, are thrown into operation by a reverse movement of the sound box after the reproduction of the record. While in the form shown, this reverse movement is imparted by an eccentric groove which forms a continuation of the sound groove, it is to be expressly understood that the invention is not limited to the use of an eccentric groove of the type now extensively employed for actuating brake mechanism.

Referring to Fig. 9, the plate 30 is provided with a laterally projecting lug 177, to the lower surface of which is pivoted, by a vertically disposed pivot member 178, a supporting arm 179 that has its opposite ends bent upwardly to form ears 179a which carry horizontally disposed pins 180. The latter constitute a pivot for an arm 181 that is provided at one end with downwardly extending ears 181a which pivotally engage pins 180, and at its opposite end, with a transversely disposed plate 182 which is bent upwardly through 90 degrees as at 183, and is bent a second time through 90 degrees, in a reverse direction to form a horizontally disposed portion 184.

The arm 181 is adapted for engagement with plate 138 and cam 139 and, in order to reduce the friction between these elements, said arm is preferably provided with an opening into which is loosely fitted a ball 185 (Fig. 8) that is retained in place by a plate 186 secured to the upper surface of said arm, the ball having rolling engagement with plate 138. A suitable anti-friction device, such as a roller 187 (Fig. 3) having its upper periphery extending very slightly above plate 30, may be provided for the reciprocating slide 136, immediately below ball 185, to reduce the friction between plate 30 and slide 136 at this point.

A bell crank lever, comprising arms 188 and 189, is pivoted at its elbow to a stub shaft 190 that projects upwardly from and is carried by arm 181. Preferably, a spring 188' may be connected at one end to arm 188 and at its opposite end to arm 181 to resist pivotal movement of the bell crank lever about pivot 190. In one position the arm 188 is adapted to engage the free end of pawl 152 whereby the latter is swung about its pivot to move tooth 154 out of driving engagement with gear 155. The other arm 189 of the bell crank lever overlies arm 181, and is provided at its free end with a large, horizontally and transversely disposed portion 191, which bears on plate 182 and has formed, on its upper surface immediately below post 165, a series of ratchet teeth that are adapted for engagement with pawl 168. Pivotal movement of arms 188 and 189 about shaft 190 is limited by a pair of downwardly extending ears 193, which may be formed integral with arm 189 and which extend downwardly from the latter on the opposite sides of arm 181. Underlying the superimposed arms 181 and 189 is a plate 194 which is secured to the side of plate 30. The upper edge of plate 194 is cut away to form a stop 195 which limits movement of arms 181 and 189 toward spindle 33, thereby insuring that arm 188 will be stopped in a position for engagement with pawl 152. A notch 196, having a depth slightly less than the thickness of arm 181, is formed in plate 194 adjacent stop 195 to provide for the lowering of arm 188 into the plane of pawl 150.

152. A second stop 197 is formed at the outer end of plate 194 to limit the outward movement of arms 181 and 189, and that portion of the edge of said plate intermediate stop 197 and 5 notch 196 is preferably inclined downwardly toward said stop to facilitate outward movement of said arm.

During the reproduction of the record, the tone arm and post 165 swing inwardly due to the 10 driving force exerted on the stylus by the spiral sound groove. Due to the inclination of the series of teeth 192, the pawl 168 rides freely over the same. Upon the completion of the reproduction, the stylus moves into the eccentric groove 15 and thereby receives a reverse movement, which is transmitted to post 165 and pawl 168. The latter now engages one of the teeth 192 thereby swinging bell crank lever 188, 189 about its pivot and moving the arm 188 out of engagement with 20 pawl 152. Spring 157 now forces tooth 154 into driving engagement with gear 155, starting the gear train which reciprocates slide 136 and moves cam 139 into engagement with ball 185. The movement of the latter up the inclined surface 25 139a of cam 139, swings arm 181 upwardly, about pivots 180, out of notch 196 in plate 194. This upward movement is transmitted, through arm 189, to post 165, lever 171 and cam 175, to the sound box 40, thereby raising the stylus out of 30 engagement with the record disk. Ball 185 now rests against the ridge portion 139b of the cam, and the continued outward movement of slide 136 acts through these elements, to swing arms 181 and 189 outwardly into engagement with 35 stop 197, the sound box and tone arm being carried along by engagement of the post 165 with the vertical shoulder at the inner end of portion 191 of arm 189. Pawl 168 is so formed that when plate 191 is raised to lift the sound box from the 40 record the toe of the pawl is out of engagement with the teeth 192 so that movement of plate 191 to the left, (Fig. 9) as will be described more fully hereafter, is not effective to carry the post 165 and tone arm to the left with it.

45 The parts are now in position to permit removal of the played record and the transfer of the next record to playing position. The slide 136 continues its outward movement to perform this transfer operation and, since arms 181 and 50 189 are held against further swinging, the ridge 139b of cam 139 is forced underneath the ball 185 and continues its outward movement for a predetermined distance. As previously pointed out, slide 136 has its movement reversed simultaneously with the initiation of the movement of the new record toward the turntable, and as the record is deposited on the latter ridge 139b has 55 returned to a position to reengage ball 185 (Fig. 8), and swing arms 181, 189 inwardly.

60 Preferably, means are provided which, in the form shown, are manually adjustable, for returning the sound box and tone arm to starting position for either small or large size records. For this purpose, the portion 184 of arm 181 has 65 pivoted thereto, as at 198, a curved and horizontally disposed arm 199 which is adapted for engagement, intermediate its ends, with member 166 carried by post 165. Arm 199 is also adapted for engagement, adjacent its free end, with a stop 70 pin 200 that extends downwardly from one arm 201a of a bell crank lever that is pivoted at 202 to the lower face of a plate 203 which is preferably attached to the under surface of motorboard 75 27. A spring 204, which is secured at one end to arm 199 and at its opposite end to portion 184,

tends to move said arm in a clockwise direction into engagement with pin 200.

The other arm 201b of the lever carried by plate 203 is pivoted to one end of a rod 205 which has its opposite end connected to the short arm 80 of bell crank lever 91 (Fig. 3) which is adapted for adjustment by means of the knurled head 90a of shaft 90.

A bar 206 (Fig. 10) is slidably secured to the lower face of plate 203 as by means of flat-headed screws 207 which extend loosely through slots 208 in said bar. Pivotally secured to the latter, adjacent one end thereof, is a lever 209 which is yieldingly held in a predetermined position by means of a coil spring 210 that is fixed at one end to bar 206 and at its opposite end to one end of said lever 209. The bar 206 is preferably adjustable with pin 200 and for this purpose said pin has pivotal engagement with said bar.

During the playing of a record, arm 199 yieldingly engages stop pin 200 (Figs. 2 and 9) but when arms 181 and 189 are swung outwardly, in a manner described above, arm 199 is carried outwardly by arm 181 and is disengaged from pin 200, the action of spring 204 being limited 100 by engagement of said arm 199 with the upstanding portion 191a of plate 191. Member 166 carried by post 165 is moved into engagement with arm 199, after said member wipes past the free end of lever 209, due to the movement 105 of arms 181 and 189. As the two latter arms are swung inwardly by engagement of ball 185 and cam 139, arm 199 is carried inwardly and acts through member 166 on post 165 to move the sound box inwardly. During the inward 110 swinging movement of arms 181 and 189 the post 165 is maintained in raised position and the toe of pawl 168 is out of engagement with teeth 192 whereby plate 191 and teeth 192 are not effective directly to swing the tone arm inwardly. Arm 199 next engages pin 200 which has 115 been adjusted for a large or small size record, whereupon said arm is no longer effective to move post 165 as it moves about its pivot 198 in an anticlockwise direction due to the continuing inward movement of arm 181. The arm 199 is thus disengaged from post 165 as the sound box reaches starting position, but at this time the enlarged portion 166 of post 165 has been moved into engagement with lever 209 and the tone 120 arm is held by said lever in starting position. The movement of arms 181 and 189 continues until they drop into notch 196, whereupon the weight of the sound box lowers the stylus into engagement with the rotating record. This 125 movement is sufficiently retarded, however, to prevent damage to the record. Just prior to the engagement of the stylus with the record, arm 188 moves into engagement with pawl 152, thereby moving tooth 154 out of driving engagement 130 with gear 155. As the arm 181 drops into notch 196, plate 191 carried by said arm is lowered and this permits post 165 and the enlarged head 166 carried thereby to be moved downwardly under the force of spring 169. The shoulder formed 135 by the upper end of head 166 drops below the end of lever 209, thus freeing the tone arm for inward movement over a record tablet.

140 It will be understood that when it is desired to play large size records shaft 90 is moved in such a direction that pin 200 is swung away from the turntable, whereby arm 199 will be moved out of driving engagement with the tone arm more quickly than when said pin is adjusted for small size records. This adjustment of pin 200 also 145 150

results in movement of lever 209 to a suitable position for yieldingly and momentarily retaining the sound box at the starting position.

Operation.—If all the records have been removed from the magazine, spider 46 is manually moved toward plate 42 against the tension of spring 51 until locked in its innermost position by means of pin 53. A suitable number of selected records are then placed on the projecting end of pin 48 and the operator presses thumb piece 52a to release spider 46, whereupon the latter is forced outwardly, against the adjacent surface of the inner record, by means of spring 51. The records are now yieldingly held in the position illustrated clearly in Figs. 1 and 19. An additional record may also be placed on the turntable if desired and the sound box moved inwardly until the stylus is in engagement with the beginning of the groove of the record.

It will be assumed that the record placed on the turntable, and those mounted on pin 48, are of the small size, or of 10 inch diameter. The knurled head 90a is adjusted accordingly, and bar 94 is thereby moved outwardly so that pin 103 is clear of cam 98, and cam 101 occupies the position illustrated in Fig. 8, where it will not be engaged by cam 85 as the transfer member 59 is swung about its pivots. Simultaneously with the movement of bar 94, rod 205 swings the bell crank lever 201a, 201b to properly adjust pin 200 and lever 209.

The motor switch (not shown) which may be of any suitable or well known type, is then closed to supply power to the electric motor 28, and the sound box is moved by hand to such a position that the needle or stylus is brought into engagement with the beginning of the sound groove of the record. This latter is not essential, however, since the tone arm control mechanism will automatically move the stylus into proper position if it is not so moved by hand.

As the reproduction of the record is completed, the stylus moves into the eccentric groove adjacent the center of the record, and the reverse movement thus imparted to the tone arm causes pawl 168 to engage ratchet 192 and swing bell crank lever 188, 189 about its pivot 190. As arm 188 moves out of engagement with the free end of pawl 152, spring 157 moves the tooth 154 into engagement with gear wheel 155 and a driving connection for the gear train is established.

The initial movement of said gear train and slide 136 results in cam 139 being slid underneath the ball 185 carried by arm 181, and the latter is raised, together with arm 189, out of the notch 196 in plate 194. This movement is transmitted, through post 165, to the sound box whereby the stylus is lifted out of engagement with the record. Continued movement of slide 136 swings the arms 181 and 189 about the vertical pivot 178, and due to the engagement of the shoulder on portion 191 of arm 189 with the post 165, the sound box and tone arm are swung clear of the record. In this swinging movement the portion 166 of post 165 readily moves past the free end of lever 209 and comes into engagement with arm 199. When arms 181 and 189 engage the stop 197, further movement of slide 136 forces the ball 185 over the raised portion 139b of cam 139 (Fig. 8).

No movement of the record transfer means occurs until the tone arm is clear of the record, this delayed action being insured by means of the notch 144 formed in bar 140 which permits considerable movement of members 134a and 145 before the latter engages the end wall 144a of

said notch. When this engagement occurs, the tone arm and sound box are clear of the record and movement is now imparted to record transfer member 59 to swing the same upwardly about the pivots 63. As hoop 59 swings upwardly it engages the lower face of the record on the turntable, and jaws 68 engage the inner or lower edge of the record. Immediately thereafter, as arm 82 clears the plate 83, hook 73 is forced into engagement with the outer or upper edge of the record by means of spring 79. The record is thus lifted from the turntable. As the record hoop continues its upward movement finger 112 moves along the surface of cam 116 and into engagement with stop pin 114 of the arm 111. When thus engaged, finger 112 and arm 111 constitute a rigid arm which is partially rotated by the engagement of said finger with the cam 116. This movement of arm 111 results in the rotation of shaft 106, which acts through arm 107 and pin 108 to slide cam 109 longitudinally in the direction of the arrow shown in Fig. 17. The cam surfaces 109a and 109b force rods 70 and 71 downwardly, thereby swinging jaws 68 and 69 about their pivots until the upper ends of said jaws are flush with the upper surface of plate 59a. At this time the record transfer member 59 has assumed substantially the position illustrated in dotted lines in Fig. 2, whereupon the force of gravity slides the record downwardly through slot 117 into the receptacle 118.

Rod 140 continues its forward motion and the record transfer member 59 is swung into engagement with the outer record supported by the magazine. Plate 42 is swung about its pivots, against the tension of springs 58 by this engagement, and simultaneously, the jaws 68 move under the lower edge of the outer record since, as the hoop assumes an upright position, finger 112 snaps over the upper end of cam 116 to release shaft 106 and permit the springs 72 to return the jaws 68 and 69 to their normal position projecting above the upper surface of plate 59a. Due to the axis of the record transfer member 59 being positioned at a distance from the pivotal axis of the magazine, the jaws 68 have an upward movement relative to the records mounted in the magazine. This upward movement of jaws 68 carries the outer record upwardly until the center hole in the same clears the upper edge of the toe 48a of rod 48 and the spring 51 frees the record from the rod 48. The pressure of the hoop acts on hook 73 to snap the same over the upper edge of the record. The record is now disengaged from pin 48 and held between jaws 68 and hook 73, whereupon hoop 59 begins its return movement toward the turntable, since at this time plate 145 is moving away from the wall 144a of notch 144. Spring 150, which has been placed under compression by the engagement of rod 147 with cam 151, acts on the bar 140 to move the same in a reverse direction and the hoop 59 is therefore moved reversely toward the turntable, finally resuming a horizontal position as is clearly illustrated in Fig. 2, the record being deposited on the turntable as the hoop passes by the upper surface of the same.

Slide 136 at this time has returned toward its starting position a sufficient distance to bring the raised portion 139b of cam 139 into engagement with the ball 185, and the arms 181 and 189 are swung inwardly toward the turntable spindle 33. The spring-pressed arm 199 now engages the lower end of post 165 and the tone arm 150

is moved inwardly toward the outer edge of the record or toward starting position. This movement continues until arm 199 engages the downwardly extending pin 200, whereupon no further movement is imparted to the post 165 and the tone arm. The needle or stylus is now in raised position above the starting point. The inertia of the tone arm and sound box is not effective to move the sound box past starting position due to the engagement of the lower end of post 165 with the spring-held lever 209. Arms 181 and 189 continue their movement, however, toward the turntable spindle until they engage stop 195 formed on plate 194. The continued movement of slide 136 forces ball 185 over the cam 139 and as said ball passes down the inclined face of said cam, arms 181 and 189 move by gravity into the notch 196 formed in plate 194. Substantially simultaneously with this movement, arm 188 engages the free end of pawl 152, and due to the movement of the latter, tooth 154 is forced out of driving engagement with gear 155 and the downward movement of arms 181 and 189 permits spring 169 to force post 165 downwardly, thereby acting through lever 171 to disengage roller 174 from cam 175 and permit the sound box to be gently lowered into engagement with the rotating record.

The record is now reproduced and when the stylus enters the eccentric groove at the end of the record the automatic movements are again initiated in the manner described above. The cycle of operations is repeated until all of the records in the magazine have been played. If the record transfer member 59 returns to its horizontal position in the plane of the turntable 34 without depositing a record on said turntable, the tone arm is swung inwardly to starting position in the normal manner and the sound box is lowered but no further movement of the automatic mechanism takes place since no force is present to carry the stylus inwardly toward the turntable spindle.

If it is desired at any time to discontinue the playing of a record it is only necessary to raise the sound box by hand and move it in toward the turntable spindle and then return it a slight distance to simulate the movement given to the stylus by the eccentric groove in the record. The automatic mechanism will be thrown into operation to swing the tone arm clear of the turntable, to discharge the record thereon into the receptacle 118, and transfer another record to playing position.

If it is desired to supply the magazine with large size or 12 inch records, the knurled head 90a is rotated to bring pointer opposite the indication corresponding to the large size records. This movement of the pointer and knurled head 90a results in the rotation of shaft 90 which acts through pin 104 to slide the bar 94 inwardly toward lug 61. This adjustment of the machine should be made when the hoop is in a horizontal position, in the plane of the turntable, since at this time member 105 holds the toe of dog 104 out of engagement with the notch 94a in bar 94. The movement of the bar inwardly causes pin 103 to ride up on the cam 98 and assume a position on the horizontal portion 98b of said cam, with the cam 101 in a position to be engaged by cam 85. The rotation of shaft 90 also acts through rod 205 to swing the bell crank lever 201a, 201b about its pivot, thereby moving the pin 200 outwardly from the periphery of the turntable. Bar 75 206 and pivoted lever 209 are moved in corre-

spondence with the pin 200. As the record transfer member 59 moves upwardly to remove a record from the magazine, cam 85 engages the cam 101 and shaft 84 is partially rotated. Rotation of shaft 84, which takes place in the direction of the arrow in Fig. 17, acts through arm 86 and pin 87 to move cam 88 longitudinally. This movement of cam 88 causes the cam surface 88a to engage shaft 70 and swing the jaws 68 downwardly about their pivots until the upper ends of said jaws are flush with the upper surface of plate 59a. The jaws 68 therefore do not interfere with the engagement of jaws 69 with the lower edge of the large size record, and these jaws 69 operate in a manner similar to the jaws 68, as pointed out above, to remove the record from the magazine. Hook 73, which engages the face of the large size record, is forced downwardly against the light pressure of the leaf spring 77 until its upper end is flush with the upper surface of the lug 59b, said hook swinging about its pivots 74 and 76. The outer hook 78 engages the upper edge of the record and the same is positively carried by the record transfer member 59 to the turntable.

When it is desired to discontinue the playing of the machine and close the cabinet, latch 57 may be raised by hand and the magazine structure may then be rotated to a position over the turntable. In this position the magazine does not interfere with the closing of the cover 26.

It will be perceived that a sound reproducing machine has been provided which includes novel magazine means for supporting a plurality of records in position to be moved into cooperative engagement with the sound reproducing instrumentalities and that no adjustment of the magazine structure is required to adapt the same to records of different diameters. The machine embodies novel mechanism for disengaging the record tablets from the magazine, the record transfer member having an upward movement substantially parallel to the face of the record tablet for this purpose, and for positively carrying the records to playing position on the turntable. The transfer mechanism also embodies means for positively moving the record, after the same has been reproduced, from the turntable and discharging the same by gravity into a suitable receptacle that is preferably located below the plane of the motorboard. The record engaging means are so constituted that the same do not interfere with the sliding movement of the record tablet from the transfer hoop into the record receptacle. Means are also provided for raising the sound reproducing instrumentalities, for swinging the same clear of the record and subsequently returning the same to starting position on the record. Manual means are provided for so adjusting the mechanism that the sound reproducing instrumentalities may be moved to different starting positions depending on the size of the records it is desired to play. Novel means are provided for driving the record transfer mechanism, and the tone arm control mechanism, from the power means employed for rotating the turntable, said means being so constructed that the operations are positively performed in the proper sequence. Only one driving element or motor need be employed. The device is extremely compact and pleasing in appearance.

While only one illustrative embodiment of the inventive idea has been described in detail, the scope of the invention is not limited to such embodiment or otherwise than by the terms of the

appended claims. While the preferred embodiment of this invention embodies the various features heretofore described, certain features of the invention may be employed without other features thereof. For example, various other mechanism for controlling the movement of the sound box and tone arm may be employed in connection with the mechanism heretofore described for changing the record tablets.

10 Changes may be made in the construction, proportion and arrangement of parts without departing from the spirit of the invention: Thus the sound reproducing instrumentalities have been shown as of the type designed to reproduce 15 sound from a laterally undulating trace but other types of sound reproducing devices may be employed; the tone arm has been illustrated as of the type including a gooseneck but other forms of tone arm and reproducer mountings may be 20 employed by suitably varying certain elements of the structure heretofore described; while the mechanism for returning the sound reproducing instrumentalities to starting position has been described as adapted for one or two sizes of record 25 tablets, for example 10 or 12 inch record tablets, the invention is applicable to other sizes of tablets and by suitable modification may be employed to reproduce sound from more than two sizes of tablets. Other mechanical forms of 30 the present invention will readily suggest themselves to those skilled in the art as a result of the invention disclosed herein and it is therefore to be expressly understood that reference is to be had to the appended claims for a definition 35 of the limits of the invention.

What is claimed is:—

1. In a sound reproducing machine embodying a turntable, a magazine for supporting a plurality of disk record tablets in a position to 40 be transferred into cooperative relation with sound reproducing instrumentalities comprising an upright member inclined toward said turntable, a downwardly inclined record holding pin operatively secured to said member, a toe formed 45 on said pin, said pin being adapted to receive and support a plurality of record tablets in an inclined position with the outer face of the record tablet closest the turntable in engagement with said toe, and means for releasing and transferring a tablet from said pin downwardly onto 50 said turntable.

2. In a sound reproducing machine embodying sound reproducing instrumentalities, means for holding a record tablet in position to be moved 55 into cooperative relation with said instrumentalities comprising an upright member, a downwardly inclined device, carried by said upright member, having a portion adapted to extend through the center hole in said record tablet, and 60 a transversely extending rigid toe on the outer end of said portion adapted to engage the face of a record tablet adjacent the periphery of the center hole therein to retain the tablet on said pin against displacement therefrom by gravity.

3. In a machine of the class described embodying sound reproducing instrumentalities, a magazine for holding a plurality of record tablets in position to be moved into cooperative relation with said instrumentalities comprising a pivotally mounted upright member, means normally preventing pivotal movement of said upright member, a record tablet support mounted on the upright member adjacent the upper end of the latter, said support being inclined downwardly from the horizontal and extending toward the

sound reproducing instrumentalities, and an upwardly extending toe on the outer end of said support adapted to engage the face of a record tablet adjacent the periphery of the center hole whereby said record tablets are maintained on said support in an inclined position. 80

4. In a sound reproducing machine embodying sound reproducing instrumentalities, a magazine for supporting one or more record tablets in position to be transferred into cooperative relation with said instrumentalities comprising a device having a portion adapted to extend through the center hole in said record tablet or tablets, means for pivotally supporting said device, yielding means normally maintaining said device in a downwardly inclined position, means associated with said extending portion for engagement with a record tablet thereon to prevent gravitational displacement of a tablet therefrom, and yielding means normally urging said tablets into engagement with said last named means. 85 90 95

5. In a sound reproducing machine embodying sound reproducing instrumentalities, a magazine for holding a plurality of disk record tablets positioned to be transferred into cooperative relation with said instrumentalities, said magazine comprising a pivotally mounted plate, means thereon for supporting record tablets in inclined position, latch means for retaining said plate in operative position, and resilient means for normally retaining said plate in an inclined position and in engagement with said latch means. 100 105 110

6. In a sound reproducing machine embodying sound reproducing instrumentalities, a magazine for holding record tablets in inclined position, for movement into cooperative relation with said instrumentalities, comprising a downwardly inclined member having a toe on the outer end thereof, a spider associated with said inclined member, resilient means for moving said spider 115 toward said toe whereby a record tablet is yieldingly held on said member, and releasable means for locking said spider against movement.

7. In a sound reproducing machine embodying sound reproducing instrumentalities, means for holding a record tablet comprising a bracket member, an inclined record support mounted on the bracket member and having a portion adapted to extend through the center hole in the record tablet, an upwardly extending element on the 125 outer end of said portion adapted to engage the face of a record tablet adjacent the periphery of the center hole therein to prevent accidental displacement of a record tablet from said support, and means for transferring a record tablet from 130 said support to cooperative relation with said sound reproducing instrumentalities, said last named means including means adapted to engage the edge of the record tablet and move it upwardly relative to said support to disengage the 135 face of the record tablet from said upwardly extending element.

8. In a sound reproducing machine, the combination, with sound reproducing instrumentalities, of magazine means for holding a plurality 140 of record tablets in position to be moved into cooperative relation with said instrumentalities, means for pivotally mounting said magazine means, transfer means for moving a record tablet from the magazine means into and out of cooperative relation with said instrumentalities, and means for swinging said transfer means into engagement with a record tablet supported by the magazine means, the engagement of the transfer 145 150

means with the record tablet causing pivotal movement of said magazine means.

9. In a sound reproducing machine, the combination with sound reproducing instrumentalities and a turntable, of magazine means for holding a plurality of record tablets in position to be moved into cooperative relation with said instrumentalities, means for pivotally mounting said magazine means, transfer means for moving a record tablet from the magazine means to said turntable, and means for swinging said transfer means into engagement with the foremost record tablet supported by the magazine means, the engagement of the transfer means with the record tablet causing pivotal movement of said magazine means and movement of said foremost tablet relative to the magazine means to free the tablet therefrom.

10. In a sound reproducing machine, the combination with sound reproducing instrumentalities, of means for holding a plurality of record tablets in position inclined to the vertical, and means for engaging the edge of and moving one of said record tablets upwardly relative to the remaining tablets held by said first named means and subsequently swinging said tablet into cooperative relation with said instrumentalities, said tablet swinging means being adapted to move said record tablet out of cooperative relation with said instrumentalities.

11. In a sound reproducing machine, the combination with sound reproducing instrumentalities, of means for holding a plurality of record tablets in position inclined to the vertical, and means for engaging the edge of and moving one of said record tablets upwardly relative to the remaining tablets held by said first named means, and thereafter moving said tablet into cooperative relation with said instrumentalities.

12. In a sound reproducing machine, the combination with sound reproducing instrumentalities, of magazine means for holding a plurality of record tablets, transfer means for moving a record tablet from said magazine into cooperative relation with said instrumentalities, said transfer means embodying means adapted to directly engage the edge of a record tablet to be transferred and to push only said record tablet in a relatively upward direction to disengage the same from the magazine, and means for actuating said transfer means.

13. In a sound reproducing machine, the combination with sound reproducing instrumentalities, of a magazine for holding a plurality of record tablets, transfer means for moving said record tablets in succession from the magazine into cooperative relation with said instrumentalities, said transfer means comprising a member pivoted at a distance from the magazine, means carried by said transfer member for engagement with the edge of the record tablet to be transferred, and means for swinging said tablet engaging means into engagement with the record tablet, the engagement of said means with said record tablet acting to move the tablet upwardly relative to the magazine whereby said tablet is disengaged from the magazine.

14. In a sound reproducing machine, the combination with a magazine for holding a plurality of record tablets and sound reproducing instrumentalities, of transfer means for moving said record tablets in succession into cooperative relation with said instrumentalities comprising a record transfer hoop, means projecting from the surface of said hoop and adapted for engagement

with the edge of a record tablet, a pivotal support for said hoop positioned at a distance from said magazine, and means for swinging said hoop and means into engagement with a record tablet to disengage the same from the magazine by the action of said projecting means on the edge of said tablet.

15. In a sound reproducing machine, the combination with a magazine for holding a plurality of record tablets and sound reproducing instrumentalities, of transfer means for moving said record tablets in succession into cooperative relation with said instrumentalities, said transfer means comprising a transfer member pivotally mounted on a single axis, means for moving said member about its axis to and from said magazine, and means on said member for engaging the edge of the foremost tablet in said magazine and moving the same in its own plane to free it from said magazine.

16. In a sound reproducing machine of the type wherein a magazine is provided for holding a plurality of record tablets in position to be transferred into cooperative relation with sound reproducing instrumentalities, means for actuating said sound reproducing instrumentalities, transfer means for moving said record tablets in succession into cooperative relation with said instrumentalities comprising a pivotally mounted transfer member, actuating means for moving said member about its axis to and from said magazine, of means on said member for engaging the edge of the foremost tablet on said magazine and pushing the same in its own plane by reason of said pivotal movement to free it from the magazine, and means actuated by reverse movement of said instrumentalities for initiating the operation of said last named actuating means.

17. A sound reproducing machine comprising, in combination, a magazine for holding a plurality of record tablets, sound reproducing instrumentalities, a turntable, transfer means for moving said record tablets into cooperative relation with said instrumentalities, said transfer means including a hoop pivoted intermediate the record magazine and turntable, means carried by said hoop for engagement with a record tablet supported by the magazine, the engagement of said means with said tablet being adapted to move said tablet upwardly to disengage the same from the magazine, and means for swinging said hoop to deposit said record tablet on the turntable.

18. In a machine of the class described wherein a magazine is adapted to support a plurality of records in position to be transferred onto a turntable and into cooperative relation with sound reproducing instrumentalities, the combination with said instrumentalities of record transfer means for moving a record from the magazine to said turntable and for discharging the record therefrom comprising an annular member, means for swinging said annular member in a vertical arc, means carried by said annular member for engagement with the edge of a record tablet to be transferred, said means normally projecting above the upper surface of the annular member, and means for moving said tablet engaging means to a position wherein a tablet carried by the annular member slides therefrom under the action of gravity.

19. In a machine of the class described wherein a magazine is adapted to support a plurality of records in position to be transferred into cooperative relation with sound reproducing instrumentalities, the combination of record transfer

- means for moving a record from said magazine into cooperative relation with said instrumentalities and for moving said record out of cooperative relation with said instrumentalities, comprising an annular member, record engaging means carried by said member and normally projecting above the upper face of the same, and means for swinging said annular member to a position wherein said record slides from the annular member over said record engaging means. 5 20. In a sound reproducing machine of the magazine type, record transfer means comprising a member mounted for swinging movement in a vertical arc, record engaging means projecting upwardly from the surface of said member for engagement with the edge of a record, means for swinging said member from a horizontal position to a substantially upright position, and means actuated during the swinging movement 15 for producing relative movement between said record engaging means and a record supported on said member. 21. In a sound reproducing machine of the magazine type, record transfer means comprising a pivoted transfer member, means carried by said member and adapted for engagement with a small size record, means carried by said member and adapted for engagement with the large size record, and means for producing relative movement between a record carried by said member and said record engaging means whereby said record may be moved by gravity from said transfer member. 22. In a sound reproducing machine of the magazine type, record transfer means comprising a pivotally mounted hoop, a pair of jaws carried by said hoop for engagement with a small size record, a pair of jaws carried by said hoop for engagement with a large sized record, means for swinging said hoop and means for moving said first named jaws out of record engaging position actuated by the movement of said hoop. 23. In a sound reproducing machine of the magazine type, record transfer means comprising a pivotally mounted hoop, means carried by said hoop for engagement with a small size record, means carried by said hoop for engagement with a large size record, means for swinging said hoop, and means for optionally holding said first named means out of record engaging position during the swinging movement of the hoop. 24. In a sound reproducing machine of the magazine type, record transfer means comprising a transfer hoop, a pair of jaws carried by said hoop for engaging small size records, a second pair of jaws carried by said hoop for engaging large size records, means for simultaneously moving both of said pairs of jaws out of record engaging position, and means for swinging said hoop. 25. In a sound reproducing machine of the magazine type, record transfer means, and driving means for said transfer means comprising a driving motor, a slide, means operatively connected to said slide and driving means for reciprocating the slide, and means for pivotally connecting said reciprocating slide and the transfer means. 26. In a sound reproducing machine of the magazine type, record transfer means including a pivoted transfer member, and means for swinging said transfer member comprising a driving motor, a slide, means including a clutch having operative engagement with the driving motor for reciprocating said slide, means for pivotally connecting said transfer member and slide, and means for disengaging said clutch from driving connection with the driving motor. 27. In a sound reproducing machine of the magazine type, record transfer means including a pivotally mounted member for moving a record tablet to, and displacing the same from, playing position, and means for actuating said record transfer member including a driving motor, a slide, means adapted to be engaged and disengaged with said driving motor for reciprocating said slide, and a lost motion connection for operatively connecting said slide and transfer member. 28. In a sound reproducing machine of the magazine type, record transfer means including a pivoted transfer member adapted to swing in a vertical arc, and means for actuating said transfer member including a driving motor, clutch means adapted to be engaged and disengaged with said driving motor, a gear train actuated by said clutch means, a slide adapted to be reciprocated by said gear train, and a pin and slot connection operatively connecting said slide and transfer member. 29. A sound reproducing machine comprising sound reproducing instrumentalities, a turntable adapted to rotate a record tablet in reproducing position, and means for moving said instrumentalities into and out of cooperative relation with said record tablet comprising a driving motor for actuating said turntable, a slide, means operatively connecting said slide and driving motor for reciprocating the slide, means actuated by movement of the sound reproducing instrumentalities for placing said last named means in driving relation with said motor, and means actuated by said slide for raising, swinging and lowering said sound reproducing instrumentalities. 30. In a sound reproducing machine, the combination with a turntable and sound reproducing instrumentalities, of means for moving said instrumentalities relative to said turntable comprising a driving motor, a slide, mechanism actuated by said motor for reciprocating said slide, a bell crank lever controlled by said instrumentalities for operatively connecting said mechanism and motor, cam means carried by said slide, and means actuated by said cam means for raising and swinging said instrumentalities. 31. In a sound reproducing machine, the combination with means for rotating a record tablet and sound reproducing instrumentalities, of means for moving said instrumentalities into and out of cooperative relation with a record tablet comprising a reciprocating slide, means operatively connecting said slide and record rotating mechanism, a pivotally mounted arm adapted to operatively engage said instrumentalities, means operatively connecting said slide and arm for swinging the latter, a member carried by said arm, and an adjustable element adapted to engage said member and swing the same relative to said arm. 32. In a sound reproducing machine, the combination with record rotating means and sound reproducing instrumentalities, of means for raising and lowering said sound reproducing instrumentalities comprising a vertically disposed post slidably carried by said instrumentalities, a driving motor, a slide operatively connected thereto, an arm adapted for engagement with said slide, said arm being adapted to engage said post, and means actuated by movement of the post for establishing a driving connection between the rec- 80 85 90 95 100 105 110 115 120 125 130 135 140 145 150

ord rotating means and said slide, said arm being adapted to be raised by said slide.

33. In a sound reproducing machine, the combination with record rotating means and sound reproducing instrumentalities, of means for moving said instrumentalities into and out of cooperative relation with a record comprising a reciprocating slide, a horizontally movable arm operated thereby, a pivoted member secured to said arm and adapted to move said instrumentalities toward the starting point on the record, and means controlled by reverse movement of said instrumentalities for establishing a driving connection between said record rotating means and said slide.

15 34. In a sound reproducing machine, the combination with record driving means, of sound reproducing instrumentalities, means for swinging said sound reproducing instrumentalities away from a record actuated by said driving means comprising a reciprocating slide and a horizontally swinging arm actuated by the slide, means for swinging said instrumentalities toward the record comprising a pivoted member carried by said arm adapted for engagement with said instrumentalities, and means actuated by movement of said instrumentalities for operatively connecting said driving means and said slide.

30 35. In a sound reproducing machine of the type wherein a magazine is provided for holding record tablets in a position to be moved into cooperative relation with sound reproducing instrumentalities, the combination with said magazine of transfer means, control means for said instrumentalities, a reciprocating slide adapted for operative connection with said instrumentalities and said transfer means, means for reciprocating said slide, and means actuated by reverse movement of said instrumentalities for initiating the operation of said last named means.

40 36. In a sound reproducing machine, the combination of record rotating means and sound reproducing instrumentalities, of means for moving said instrumentalities into and out of cooperative relation with a record comprising a slide, means actuated by said rotating means for reciprocating said slide, cam means carried by the slide, an arm actuated by the cam means for raising and swinging said sound reproducing instrumentalities, a member pivotally mounted on said arm and adapted to be actuated by the reverse movement of said instrumentalities, and means actuated by said pivotally mounted member for establishing driving connection between the rotating means and said first named means.

35 37. A sound reproducing machine of the magazine type comprising record transfer means including a member adapted to move a record to and from reproducing position, sound reproducing instrumentalities, a turntable, means for rotating said turntable, means for actuating said transfer member and for moving said instrumentalities into and out of operative relation with a record on said turntable comprising a slide adapted to be reciprocated by said rotating means, means operatively connecting said slide and transfer member, and means operatively connected to said slide for raising and swinging said instrumentalities.

40 38. In a sound reproducing machine, a record turntable, means for rotating said turntable, sound reproducing instrumentalities including a tone arm and a sound box, and means for raising and lowering said sound box relative to the turntable comprising a post slidably carried by said tone arm, a cam operatively connected to said

sound box, a cam actuating lever operated by movement of said post, and means operatively connected to said turntable rotating means for raising said post.

39. In a sound reproducing machine, a record 80 turntable, means for rotating said turntable, sound reproducing instrumentalities including a tone arm and a sound box, and means for raising and lowering said sound box relative to the turntable comprising a post slidably carried by said tone arm, a cam operatively connected to said sound box, a cam actuated lever operated by movement of said post, cam means actuated by said turntable rotating means, and means actuated by said means for actuating said post.

40. In a sound reproducing machine, a record 85 turntable, means for rotating said turntable, sound reproducing instrumentalities including a tone arm and a sound box, and means for raising and lowering said sound box relative to the turntable comprising a post slidably carried by said tone arm, a cam operatively connected to said sound box, a lever adapted for operative engagement with said cam and post, a slide, means operatively connected to said turntable rotating 90 means for reciprocating said slide, a cam carried by said slide, and means actuated by said cam for raising said post.

41. In a sound reproducing machine of the type wherein a motor is employed for 105 rotating a turntable carrying a record adapted to coat with sound reproducing instrumentalities, the combination with said motor of means for swinging said instrumentalities away from starting position comprising 110 a slide, means adapted to be operatively connected to said motor for reciprocating said slide, cam means carried by said slide, a swinging arm adapted for operative engagement with said instrumentalities and said cam means, and means 115 actuated by movement of said instrumentalities for operatively connecting said second named means with said motor.

42. In a sound reproducing machine of the magazine type adapted to play different size 120 records, the combination with record rotating means and sound reproducing instrumentalities, of means for moving said instrumentalities into starting position comprising a swinging arm adapted to be actuated by said record rotating 125 means, a downwardly extending member carried by said instrumentalities, means pivotally connected to said arm and adapted to engage said downwardly extending member, and manually adjustable means adapted to be engaged by said 130 pivotally connected means whereby the latter is swung out of engagement with said downwardly extending member.

43. In a sound reproducing machine, the combination with record rotating means and sound 135 reproducing instrumentalities, of means for raising and lowering and swinging said instrumentalities including a driving motor, a slide adapted to be reciprocated by said motor, means cooperating with said slide and reproducing instrumentalities whereby reciprocation of said slide raises and returns said instrumentalities to the starting position of a record tablet on said rotating means, and means actuated by said instrumentalities for initiating the reciprocation of 140 said slide.

44. In a sound reproducing machine, the combination with record rotating means and sound reproducing instrumentalities, of means for raising and lowering and swinging said instrumentalities 150

5. **5. In a sound reproducing machine, the combination with record rotating means and sound reproducing instrumentalities, of means for raising and lowering and swinging said instrumentalities including a driving motor, a slide adapted to be reciprocated by said motor, means cooperating with said slide and reproducing instrumentalities whereby reciprocation of said slide raises and returns said instrumentalities to the starting position of a record tablet on said rotating means, and means actuated by a reverse movement of said instrumentalities for initiating the reciprocation of said slide.** 80
10. **10. 45. In a sound reproducing machine, the combination with record rotating means and sound reproducing instrumentalities, of means for raising and lowering and swinging said instrumentalities including a driving motor, a slide adapted to be reciprocated by said motor, and means cooperating with said slide and reproducing instrumentalities whereby reciprocation of said slide raises and returns said instrumentalities to the starting positions of record tablets of different diameters.** 85
15. **15. 46. In a sound reproducing machine, the combination with record rotating means and sound reproducing instrumentalities, of means for raising and lowering and swinging said instrumentalities including a driving motor, a slide adapted to be reciprocated by said motor, means cooperating with said slide and reproducing instrumentalities whereby reciprocation of said slide raises and returns said instrumentalities to the starting positions of record tablets of different diameters.** 90
20. **20. 47. In a sound reproducing machine provided with a turntable and sound reproducing instrumentalities, means for raising and swinging said sound reproducing instrumentalities from said table, including a reciprocating slide, a cam actuated thereby, means including a swinging arm positioned in the path of movement of said cam and adapted for engagement with the latter, a post extending downwardly from said sound reproducing instrumentalities, and means for operatively connecting said post and said arm.** 95
25. **25. 48. In a machine of the class described wherein a magazine is adapted to support a plurality of records in a position to be transferred onto a turntable into cooperative relation with sound reproducing instrumentalities, the combination with said instrumentalities of record transfer means for moving a record from said magazine onto said turntable comprising an annular member adapted to occupy a horizontal plane below the upper surface of the turntable during the reproduction of the record, and means for swinging said annular member upwardly into contact with the record supported by said magazine to remove said record from the magazine.** 100
30. **30. 49. In a machine of the class described wherein a magazine is adapted to support a plurality of record tablets in a position to be transferred onto a turntable into cooperative relation with sound reproducing instrumentalities, the combination with said instrumentalities of record tablet transfer means for moving a tablet from a magazine onto the turntable comprising an annular member adapted to occupy a position below the upper surface of the turntable during the reproduction of a record tablet, means for swinging said annular member upwardly to remove a record tablet from the turntable and permit the same to move by gravity into a receptacle, said last named means acting to move the annular member into engagement with the record tablet supported by the magazine, the engagement of the annular** 105
35. **35. member with said record tablet serving to move the record tablet upwardly relative to the magazine, and yielding means for initiating the return movement of the annular member toward the turntable with the record tablet supported thereon.** 110
40. **50. In a sound reproducing machine of the magazine type wherein a record tablet magazine is provided for supporting records in a position to be transferred into cooperative relation with sound reproducing instrumentalities, tablet transferring mechanism for moving the record tablet into and out of cooperative relation with said instrumentalities, said mechanism comprising an annular member adapted to occupy a position surrounding the turntable during the reproduction of a record tablet, means for swinging said annular member about a horizontal axis, and means provided on the annular member adjacent said axis for engaging the lower edge of a record tablet and raising it relative to the magazine.** 115
45. **51. In a sound reproducing machine of the magazine type, the combination with a turntable and driving mechanism therefor, of record transfer means comprising an annular member carrying means for engaging a record and retaining the same on the annular member as the record is moved thereby to the turntable, and means operatively connected to said annular member and driving mechanism for swinging said annular member in a vertical arc to discharge a record from the turntable.** 120
50. **52. In a sound reproducing machine, the combination of sound reproducing instrumentalities, a turntable, driving means for the turntable, a magazine for holding a plurality of record tablets, pivotally mounted record tablet transfer means for moving a record tablet from the magazine to the turntable, said transfer means being adapted to engage and move a record tablet upwardly to disengage the latter from said magazine, and means operatively connected to said driving means for actuating said transfer means, said transfer means being adapted to remove a record tablet from said turntable.** 125
55. **53. In a sound reproducing machine, a record magazine, record transfer means for moving the record from the magazine into cooperative relation with sound reproducing instrumentalities, said transfer means including a pivoted hoop adapted to occupy a position in the plane of the turntable while a record is being played, means carried by said hoop for positively engaging and moving a record toward and away from the turntable, and means for swinging said hoop in a vertical arc.** 130
60. **54. In a machine of the class described embodying sound reproducing instrumentalities, a record magazine, a turntable, driving means for the turntable, transfer means for moving a record from the magazine to said turntable, and mechanism actuated by said driving means for operating the transfer means, said mechanism comprising a gear adapted to be rotated by said power means, a disk having a tooth pivoted thereon, said tooth being adapted to engage said gear, a slide, means for transmitting motion from said disk to said slide, and a member operatively connecting said slide and record transfer means.** 135
65. **55. In a machine of the class described wherein sound reproducing instrumentalities are adapted to reproduce a record tablet positioned on a turntable driven by power means, and** 140

- wherein magazine mechanism is provided for supporting record tablets in a position to be moved into cooperative relation with said instrumentalities, the combination with said driving means of means for transferring a record tablet from the magazine to said turntable comprising a slide, and means for reciprocating said slide including a member actuated by said driving means and a pivoted driving member adapting to be engaged with and disengaged from the member actuated by the driving means. 5
56. A machine of the class described comprising sound reproducing instrumentalities and a turntable, a magazine for holding record tablets, transfer means for moving a record tablet from the magazine to the turntable, driving means for the turntable, means adapted to be actuated by the driving means for operating said transfer means including a disk loosely mounted on the turntable spindle, and means movably secured to the disk for operatively connecting said disk to said spindle for rotation with the latter. 10
57. In a machine of the class described wherein sound reproducing instrumentalities are adapted to reproduce a record tablet positioned on a turntable driven by power means, and wherein record transfer means are provided for transferring a record tablet from a magazine to said turntable, the combination with said transfer means of mechanism for driving the transfer means comprising a turntable spindle driven by said power means, a disk loosely carried on said spindle, a toothed member pivoted on said disk, a driving member carried by and rotatable with said spindle, and yielding means adapted to move said toothed member into engagement with said driving member. 15
58. In a sound reproducing machine embodying a turntable, sound reproducing instrumentalities, means for moving the sound reproducing instrumentalities to starting position, and manually adjustable means for varying the movement of the sound reproducing instrumentalities to play records of different diameters, said manual means including a slidably mounted bar having notches therein, means adapted to enter the notches in said bar for maintaining the latter in adjusted position, a movable stop pin and means for moving said stop pin and bar. 20
59. In a sound reproducing machine of the type provided with a magazine for holding record tablets in a position to be moved into cooperative relation with sound reproducing instrumentalities, the combination with said magazine of tablet transfer means embodying a hoop and a plurality of members carried by said hoop for engagement with a record tablet, adjustable means for determining which one of said members shall be in record engaging position, and means for actuating said transfer means. 25
60. Transfer means for a magazine machine comprising a transfer member, record engaging members carried by said member, adjustable means for adjusting said members whereby said member may transfer records of different sizes, a cam adapted to coact with said adjustable means, and means for moving all of said members out of record engaging position. 30
61. In a sound reproducing machine of the magazine type, a driving motor, a spindle driven by said motor, the upper end of said spindle having a tapered form, a turntable mounted on the spindle, a transfer member, having record engaging jaws, for moving a record from the said magazine to said turntable, and means for actuating said transfer member operatively connected to said driving motor, the engagement of the record with the tapered end of said spindle acting to move the record carried by said transfer member out of engagement with said jaws. 35
62. In a sound reproducing machine of the type wherein a magazine is employed for holding a plurality of record tablets in position to be transferred to a turntable, the combination with said turntable of a turntable spindle having a tapered upper end, a transfer member adapted to move a record tablet from said magazine to a position to engage the periphery of the center hole of the record tablet with said tapered end, jaws carried by said transfer member for engagement with the edge of a record tablet, and means for actuating said transfer member, the engagement of the record tablet with said tapered end serving to move the record tablet out of engagement with said jaws, whereupon the record tablet moves by gravity onto the turntable. 40
63. In a sound reproducing machine embodying sound reproducing instrumentalities, means for holding a record tablet comprising an inclined record support having a portion adapted to extend through the center hole in the record tablet, a laterally projecting element on the outer end of said portion adapted to engage the face of a record tablet adjacent the periphery of the center hole therein to prevent accidental displacement of a record tablet from said support, and means for transferring a record tablet from said support to cooperative relation with said sound reproducing instrumentalities, said last named means including mechanism adapted to engage the edge of the record tablet and move it relative to said support in its own plane to disengage the face of the record tablet from said laterally projecting element. 45
64. In a sound reproducing machine embodying sound reproducing instrumentalities, means for holding a record tablet comprising an inclined spindle extending through the center hole in a record tablet, a laterally projecting toe on the outer end of said spindle adapted to engage the face of a record tablet adjacent the periphery of the center hole therein, and means for directly engaging the edge of a record tablet to move said tablet in its own plane to disengage said table from said spindle. 50
65. In a talking machine, the combination of a turntable, means for supporting in face to face contact a stack of records to be played, a record transfer member pivoted at one side of said turntable and comprising a member normally underlying the edge of a record on the table, means for oscillating said member about its pivot relatively to said turntable to elevate a played record off of said turntable and discharge said record and for moving a record onto said table into playing position, sound reproducing instrumentalities, and means for moving said instrumentalities clear of the turntable in advance of oscillating said member. 55
66. In a talking machine, the combination of a turntable, means for supporting a plurality of records to be played, means for displacing edge-wise the end tablet to free the same from the other records of said plurality and for transferring the freed tablet to said turntable including a record transfer member pivoted at one side of said turntable and comprising a member normally under- 60

- lying the edge of a record on the table, means for oscillating said member about its pivot relatively to said turntable to elevate a played record off of said turntable and discharge said record and for moving a record into playing position on said turntable, sound reproducing instrumentalities, and means for moving said instrumentalities clear of the turntable in advance of oscillating said member. 5 80
- 10 67. In a talking machine, the combination of a turntable, means for supporting a plurality of records to be played, a record transfer member pivoted at one side of said turntable and comprising a member normally underlying the edge of a record on the table, means for oscillating said member about its pivot relatively to said turntable to elevate and discharge a played record from said turntable and for moving a record into playing position on said turntable, means carried by and relatively movable with respect to said transfer member for retaining a tablet on said transfer member and freeing a tablet therefrom as tablets are respectively moved into and out of playing position, sound reproducing instrumentalities, and means for moving said instrumentalities clear of the turntable in advance of oscillating said member. 15 90
- 20 68. In a talking machine, the combination of a turntable, means for supporting in face to face contact a stack of records to be played, a record transfer member pivoted at one side of said turntable and comprising a hoop normally embracing said turntable, means for oscillating said member about its pivot to elevate and discharge a played record from said turntable and for moving a record into playing position on said turntable, sound reproducing instrumentalities, means for moving said instrumentalities clear of the turntable in advance of oscillating said member, and means operated from and by continued rotation of said record after said instrumentalities reach their radially innermost position for initiating the operation of said transfer member. 25 100
- 30 69. In a talking machine, the combination of a turntable, means for supporting in face to face contact a stack of records to be played, a record transfer member pivoted at one side of said turntable and comprising a hoop normally embracing said turntable, means for oscillating said member about its pivot to elevate and discharge a played record from said turntable and for moving a record into playing position on said turntable, sound reproducing instrumentalities, means for moving said instrumentalities clear of the turntable in advance of oscillating said member, and means operated from and by continued rotation of said record after said instrumentalities reach their radially innermost position for initiating the operation of said transfer member. 35 105
- 40 70. In a machine of the class described wherein a magazine is adapted to support a plurality of records in a position to be transferred onto a turntable into cooperative relation with sound reproducing instrumentalities, the combination with said instrumentalities of record transfer means for moving records to and from said table, said transfer means including an annular member adapted to occupy a horizontal plane below the record during the reproduction of the record, and means for swinging said annular member upwardly into contact with the record supported by said turntable to remove said record from the turntable. 45 110
- 45 71. Transfer means for a magazine machine comprising a transfer member, record engaging means carried by said member, adjustable means for adjusting said record engaging means whereby said member may selectively engage and transfer records of different sizes, and means adapted to oscillate said transfer member. 50 115
- 50 72. Transfer means for a magazine machine comprising a transfer member, record engaging means carried by said member, adjustable means for adjusting said record engaging means whereby said member may transfer records of different sizes, means for oscillating said transfer member, and means for withdrawing said record engaging means from operative position during a part of the oscillation of said transfer member. 55 120
- 55 73. In a sound reproducing machine of the magazine type, record transfer means comprising a pivotally mounted hoop, means carried by said hoop for engagement with a record, a hook adapted to coact with said means for maintaining a record on said hoop, means for swinging said hoop, and means whereby said hook is disengaged from the record but remains adjacent the record while the record is in playing position. 60 125
- 60 74. In a talking machine, the combination of a turntable and rotating means therefor, a magazine for supporting a plurality of records to be played, means for engaging the edge of a tablet and displacing said tablet in its own plane to release a tablet when it is to be discharged from said magazine, means whereby the discharged tablet is moved downwardly onto the turntable into playing position, sound reproducing instrumentalities movable into and out of cooperative relationship with a tablet on said turntable, means for discharging a played tablet into a used record receptacle, and means operated by continued rotation of said rotating means after said instrumentalities reach their radially innermost position for initiating the operation of said means for discharging a tablet from the turntable and transferring a tablet from the magazine to the turntable. 65 130
- 65 75. In a talking machine, the combination of a turntable, means for supporting a plurality of records to be played and comprising means for supporting a plurality of records inclined at an angle to the horizontal, a record transfer member pivoted at one side of said turntable and comprising means for engaging the periphery of a record tablet and removing the same from said tablet supporting means, means for oscillating said member about its pivot relatively to said turntable to swing a tablet onto said turntable, and sound reproducing instrumentalities movable into and out of cooperative relationship with a tablet on said turntable. 70 135
- 70 76. In a sound reproducing machine, in combination with a record rotating means and sound reproducing instrumentalities, means for raising and lowering and swinging said instrumentalities including a driving motor, a slide provided with a cam surface, means for predeterminedly reciprocating said slide from said motor, a member projecting from said instrumentalities, and means operated by the cam of said slide and cooperating with said projecting member for raising, swinging and lowering said instrumentalities in timed sequence. 75 140
- 75 77. In a sound reproducing machine, in combination with record rotating means and sound reproducing instrumentalities, means for moving said instrumentalities radially outward beyond the periphery of said record rotating means and then inwardly into cooperative relationship 145

with the starting grooves of records of different diameters, said means including a driving motor, means operated thereby for moving the sound reproducing instrumentalities radially outward, 5 means for moving said sound instrumentalities radially inward, said last named means including a member adapted to move said instrumentalities inward to the starting position of a tablet, means adapted to be set to render said member 10 inoperative when said sound reproducing instrumentalities reach the starting position of the

record to be played, means for transferring tablets of different diameters into cooperative relationship with said record rotating means and sound reproducing instrumentalities, and means for conditioning said transfer means to handle tablets of different diameters which means is set simultaneously with said means for predetermined the starting position of said sound reproducing instrumentalities.
